UNITED STATES PATENT OFFICE.

JULIA LIVINGSTON, OF NEW YORK, N. Y.

DESIGN FOR A BELT-BODY.

SPECIFICATION forming part of Design No. 32,351, dated March 13, 1900.

Application filed February 16, 1900. Serial No. 5,536. Term of patent 31 years.

To all whom it may concern:

Be it known that I, JULIA LIVINGSTON, a citizen of the United States, and a resident of the borough of Manhattan, in the city and State 5 of New York, have invented and produced a new and original Design for a Belt-Body, of which the following is a specification.

The essential features of my design consist in a belt-body having a general tapered form 10 from the center of the back toward the front, the front ends terminating in rings, the center of the back presenting a pyramidal figure composed of a backbone extending transversely across the belt-body and ribs of varying 15 lengths projecting in opposite directions from the backbone and central ribs extending from the opposite sides of the pyramidal figure toward the rings at the ends of the belt-body.

20 In the accompanying drawings, Figure 1 represents an outside view of the belt-body. Fig. 2 represents an inside view of the belt-body.

A A' represent the tapered portions of the belt-body on opposite sides of the center of 25 the back; a a', the rings at the ends of the tapered portions; B, the rib at the back, extending transversely across the belt-body; b b', the ribs extending in opposite directions from the central rib B, and C C the central 30 ribs extending in opposite directions from the central pyramidal figure at the back toward the rings.

What I claim is—

The design for a belt-body, substantially 35 as herein shown and described.

In testimony that I claim the foregoing as my invention I have signed my name, in presence of two witnesses, this 15th day of February, 1900.

JULIA LIVINGSTON.
